ADJUSTABLE CHAIR LEG EXTENSION

Constance Hopkins Dallas, Chestnut Hill, Pa.

Application January 12, 1937, Serial No. 120,204

7 Claims. (Cl. 155—88)

My invention relates generally to adjustable attachments for use on various articles of furniture and more particularly to adjustable extensions for chair legs.

5 The use of the conventional high chair is attended with certain disadvantages. A high chair at table with the family is awkward. It generally does not match other articles of furniture; it does not lend itself to being drawn closely to 10 the table; and it usually necessitates the inconvenience of a tray. Moreover, there are intermediate stages where children are too large for the average high chair yet not tall enough for chairs used by adults; and the customary practice of using cushions, books or other articles on 15 the seat of a chair for elevating the occupant to the desired height often results in discomfort. Such a makeshift arrangement is not conducive to good manners or posture and is a distinct 20 handicap to the child receiving his first lessons on behavior at table.

The principal object of my invention is to overcome the above difficulties by providing an adjustable chair leg extension which is simple 25 in structure and operation and may be easily applied, removed, or adjusted, as occasion demands, with respect to any of the usual dining room or straight chairs found in the home. I am aware that other adjustable chair leg extensions are 30 suggested in the prior art, but their intricacy and lack of capacity for easy application to the average chair make them unsuitable for general use in the home. Furthermore, the devices heretofore suggested or employed are either unstable or 35 so elaborate and expensive to manufacture as to be impracticable, whereas the device of this invention is characterized by extreme simplicity and economy of manufacture and at the same time possesses adequate ruggedness and durability, and when removed leaves the chair in its 40 original useful condition.

Other objects and advantages of my invention will become more apparent from the following detailed description of one example of the invention and a modification thereof, reference being had to the accompanying drawings. Of the drawings:

Fig. I represents a perspective view of a conventional chair with attachments embodying my 50 invention applied thereto.

Fig. II represents an enlarged side elevation of one chair leg, partially in section, showing details of one such attachment.

Fig. III represents a further enlarged perspective view of the extension member of the attach-

ment, showing also the felt protector associated therewith.

Fig. IV represents a cross section, taken as indicated by the lines IV—IV of Fig. III.

Fig. V represents a side view of the foot portion 5 of the extension member.

Fig. VI represents a perspective view of the holding element which is attached to the chair leg end, showing the spur which sinks into the 10 chair leg.

Fig. VII represents a cross section, taken as indicated by the lines VII—VII of Fig. II; and,

Fig. VIII represents a cross section similar to that of Fig. VII, but showing a modified form of clamping means comprising a rolled metal strip 15 instead of the collars shown in Figs. I and II.

With particular reference to Figs. I and II of the drawings, there is shown a conventional chair 1 having legs 2, to each of which is applied an adjustable attachment of my invention. Each 20 such attachment comprises generally an extension member 3, a holding element 4 secured to the end of the chair leg 2, and clamping means in the form of collars 5. There is desirably interposed between the extension member 3 and the 25 chair leg 2, and between the collars 5 and the chair leg 2, a protective cushion of felt or like material as indicated at 6.

The extension member 3 is shown most clearly in Fig. III. It comprises in its preferred form a 30 bar of metal having vertically spaced slots 7 therein, the bar being curved transversely throughout its length to conform to the curvature of an ordinary chair leg. At its lower end, the extension member 3 has a rounded foot 8, 35 an enlarged view of which is shown in Fig. V. The curvature of the foot 8 is of particular advantage where the chair legs are inclined at an angle to the vertical, in which case it affords a substantial surface contact with the floor. At its 40 upper end the extension member 3 has grooves 9 in the outer surface which are designed to accommodate the collars 5 with a snug fit.

The felt protector 6 comprises a strip generally conforming to the shape of the extension member 3 and having holes 10 therein which register with the holes 7 of the extension member, and it includes additionally a split cylindrical portion 12 which surrounds the chair leg 2 within the collars 5. In an obvious manner the use of such 50 a protector permits the attachment to be applied and removed or used over a long period of time, all without injury to the chair.

The holding element 4, as shown most clearly in Figs. II and VI, comprises generally a disc por- 55

tion 13 and a hook portion 14. Within the disc portion 13 there is a countersunk aperture 15 through which a screw 16 is inserted for securing the holding element to the end of the chair leg. 5. Additionally the disc portion 13 is provided with an upstanding spur 17 which sinks into the end of the chair leg and prevents the holding element from turning about the leg end. The hook portion 14 projects upwardly and laterally and is 10 adapted to engage selectively any one of the holes 7 in the extension member 3, the engagement being such as to hold the extension member firmly against the bottom end of the chair leg 2.

The collars 5 are shown most clearly in Figs. 15 II and VII. Each collar 5 is constructed of relatively resilient material and has flanged ends 18 secured together by means of a screw 19 and nut 20. The collars 5 may be adapted to fit chair legs of various shapes and sizes. Inasmuch as they fit 20 within the grooves 9 of the extension member 3, the collars 5 are held against displacement and prevented from sliding with respect to the chair leg 2.

In Fig. VIII of the drawings, there is shown a 25 modification of the invention in which rolled metal bands 5a are employed in lieu of the collars 5. Each such band comprises a continuous strip with one end 5b bent around the extension member 3 at one of the slots 7. The strip is 30 then passed around the chair leg 2 exteriorly of the cylindrical portion 12 of the felt protector. Desirably the strip is passed twice around the leg in the manner clearly illustrated in the drawings, with the free end 5c ultimately drawn taut and rolled and swaged into the slot opening 7. 35 Such an arrangement firmly clamps the extension member 3, and it has the advantage that it can be used on chair legs of different cross-sectional shapes. Also, this form of adjustable clamping means presents a very neat appearance, particularly in view of the fact that the 40 rolled end 5c may be housed within the slot 7 in such manner that there are no unsightly projections.

45 From the above description it will be apparent that the attachments of my invention may be readily applied to and removed from the legs of different kinds of chairs. Moreover, one special advantage is that the holding element 4 may be 50 permanently applied to the leg ends of a chair, and when it is desired to elevate the chair, the extension members 3 and clamping means 5 or 5a may be quickly attached. In this connection it will be noted that the hook portion 14 of the 55 holding element 4 is so constructed that it extends clear of the floor when the disc portion 13 rests on the floor.

Although the constituent elements comprising the 60 adjustable attachments of this invention are extremely simple and may be produced at a low manufacturing cost, the attachments are nevertheless very efficient in operation and possess adequate stability. One important factor in producing such stability is that the extension members 3 are held firmly against the side of the chair leg both at the upper portion where the clamping means are employed and at the bottom of the leg where the holding element with its hook portion 65 tightly grips the extension member 3.

70 While I have described my invention with reference to one example, showing, however, two types of adjustable clamping means, it will be apparent that numerous changes or modifications may be made in the form of the attachments and the various parts thereof, and that the in- 75

vention may be applied to other articles of furniture in addition to chairs, all without departing from the spirit of the invention as defined in the annexed claims.

Having thus described my invention, I claim: 5

1. In combination with a leg for a chair or the like, an extension member having vertically spaced slots formed therein, and adapted to be selectively engaged, a holding element having a down-turned hook and attached to the leg end, 10 said hook engaging said extension member through one of said slots and holding it against said leg, and adjustable clamping means securing the upper portion of said extension member against said leg. 15

2. The invention of claim 1 characterized by the further fact that there is a protecting cushion between said leg and said extension member and between said leg and said clamping means.

3. In combination with a leg for a chair or 20 the like, a transversely curved extension member having vertically spaced slots formed therein and a rounded foot formed on the end thereof, a protecting cushion attached to the inner side of said extension member and engaging said leg, said 25 protecting cushion being formed substantially to encircle said leg at the top of the extension member and having openings formed therein to correspond with said slots, clamping means securing the upper portion of said extension member to the leg and being separated from the leg by said upper part of said protecting cushion, and holding means screwed to the leg end, said holding means having a spur to engage said leg end and consisting of a disc portion fitting over 30 the leg end and a hook portion, said hook portion extending upwardly whereby it is clear of the floor when said disc portion rests on the floor. 35

4. In combination with a leg for a chair or the like, an extension member having vertically 40 spaced slots formed therein, and adapted to be selectively engaged, said extension member having a rounded foot and being curved transversely to fit against said leg, a holding element attached to the leg end and engaging said extension member through one of said slots and holding it 45 against said leg, and adjustable clamping means securing the upper portion of said extension member against said leg.

5. In combination with a leg for a chair or the 50 like, an extension member having vertically spaced slots formed therein, and adapted to be selectively engaged, a holding element attached to the leg end and engaging said extension member through one of said slots and holding it 55 against said leg, said holding element having a spur which is sunk into the leg end to keep said holding element from turning about the leg end, and adjustable clamping means securing the upper portion of said extension member against 60 said leg.

6. In combination with a leg for a chair or the like, an extension member having vertically spaced slots formed therein, and adapted to be selectively engaged, a holding element attached 65 to the leg end and engaging said extension member through one of said slots and holding it against said leg, said holding element including a flat disc for fitting on the leg end, and an engaging hook extending up from said flat disc, 70 whereby the normal use of the leg is not impaired when the extension member is removed, and adjustable clamping means securing the upper portion of said extension member against said leg. 75

7. In combination with a leg for a chair or the like, an extension member having vertically spaced slots formed therein, and adapted to be selectively engaged, a holding element attached to the leg end and engaging said extension member through one of said slots and holding it against said leg, and adjustable clamping means securing the upper portion of said extension

member against said leg, said clamping means consisting of a metallic tape wrapped around the leg and through one of said engagement slots and a rolled end swaged into the slot opening provided by the thickness of the extension member. 5

CONSTANCE HOPKINS DALLAS.
